LABOR SAVING REPORT PAD

Ward Shaver, Tulsa, Okla., assignor to Skelly Oil Company, Tulsa, Okla., a corporation of Delaware

Application December 29, 1941, Serial No. 424,828

8 Claims. (Cl. 282—10)

This invention relates to improvements in report pads or books comprising printed forms, each set of which is to be filled in with data or information in duplicate, triplicate, or any other number where carbons are used between the sheets of each set of the forms.

My invention is particularly useful where the different sets of the sheets of the pad of forms differ in color, as for example, where the first sheet is white, the second pink, and the third canary, and after being filled in in triplicate, the first is to be detached from the pad and sent to one station or party, the second detached and sent to another station or party, and the third is to be left in the pad by the person who fills in the data or information. In some cases, instead of having varying colored paper, varying colored carbons are used. Hundreds of thousands of such pads are made by the conventional method and used in a great variety of industries.

A finished pad, under the present conventional method of making and binding same, contains sets of sheets all cut to the same size, and all sheets of which but one of each set have been perforated near one end or one side, the one unperforated sheet of each set to remain permanently in the pad and the perforated sheets are to be torn out at the perforations after the data shall have been filled in the set. To form the pad, the printed matter is first imposed upon the required number of sheets of each color, and then the sheets of each color, other than the ones that are to remain permanently in the pad, are perforated near one end or near one side. The perforations have a tendency to seal the sheets at the line of perforation and it is necessary to separate them by fanning them out, which is usually done by knocking them against a table or any other solid object. The step of fanning to unseal the perforated sheets is necessary because otherwise as the operator is collating the several sheets into sets for the pad, those that have been perforated will adhere to one another and this materially delays him in his work. After the sets are stacked in the required number, the stack is placed between the back cover and the front cover of the pad and is jogged to the end or side opposite the binding end or side in order to register one sheet with another. On account of the burs at the perforations, considerable time is required to jog them in a manner that will properly register them, one sheet with another.

Furthermore, after the pad is made and a set of the sheets therein are filled in with the data or information, then in tearing out the sheet or sheets that are to be removed, very frequently, they do not tear all the way across at the perforation line, but tear below it, with the result that in such instances, the removed sheets have

jagged edges. The jagged edges interfere with their subsequent filing or handling, especially if they are to be filed with Acco fasteners or other type of filing equipment.

5 The primary object of the present invention is to dispense with a great deal of the labor and time involved in making such pads and to eliminate other disadvantages, including those above mentioned, which are present in the use of pads made according to conventional methods.

10 With the foregoing object outlined and with other objects in view which will appear as the description proceeds, the invention consists in the novel features hereinafter described in detail, illustrated in the accompanying drawing, and more particularly pointed out in the appended claims.

In the drawing:

Fig. 1 is a top plan view of my improved pad with the cover open and with a couple of the removable sheets broken away to facilitate illustration.

15 Fig. 2 is a sectional view of a portion of the pad, taken on the line 2—2 of Fig. 1.

Fig. 3 is a transverse vertical sectional view on the line 3—3 of Fig. 1.

20 Referring to the drawing, 5 designates the back cover and 6 the front cover of my improved pad. Between these covers, I arrange a multiplicity of permanent record sheets 7 which are preferably of the same dimensions as the covers and are secured to the latter by any suitable means, such as staples 8 arranged near the end 9 of the pad. Between the sheets 7, and between the uppermost sheet 7 and the front cover 6, I arrange shorter removable sheets 10 and 11. All of the sheets 7, 10 and 11 are temporarily secured to one another by pad cement or other suitable adhesive 12 arranged at an edge of the pad other than the one 9 where the staples are located.

25 Such pad is used in connection with carbon sheets 13 and 14 which are placed between each set of leaves made up of the three leaves 7, 10 and 11, providing, of course, the spaces to be filled in with data or information is to be in triplicate. After a set has been filled in, the sheet 11 can be removed and sent to one station or party, and the sheet 10 can be removed and sent to another station or party. The record sheet 7 is not detached but remains in the pad, held by the staples 8.

30 In making my pad, the sheets 10 and 11 that are to be detached from the pad after the data shall have been filled in a set thereof, are cut slightly shorter than those 7 that are to remain as a permanent part of the pad, enough shorter to avoid their being stapled into the pad. The matter to be printed on the several sheets is printed as in the case of a conventional pad, but

none of the sheets is perforated. Afterwards, the operator collates the sheets in sets as is done under the conventional method. Then, when the desired number of sets of sheets are arranged together to form a pad, they are placed between the covers 5 and 6 and are jogged to the end or side opposite the binding end or side, thus leaving the back and front covers and the permanent sheets 7 extending at the other end or side above those sheets (10, 11) that are to be subsequently removed, and this is the space for the staples 8. Then, in order to fasten the sheets that are to be subsequently removed from the pad to the sheets that are to remain a permanent part of the pad, pad cement, or any other desirable adhesive, is applied along a portion 12 of one side or one end (other than the end or side to be stapled) of all the sheets of the pad, making the pad a side or end opening book type so far as the removable sheets are concerned. The pad is then stapled at the binding end or side. Then the required number of carbons (12, 13) can be placed between the sheets of the first set in the pad or arranged otherwise to accompany the pad, or could be obtained from any source by the party intending to use the pad.

When a set of sheets in the pad shall have been filled in by the party responsible for supplying the data or information, he removes the removable sheets (10, 11) by simply pulling them loose at the side or end where the cement or other adhesive has been applied.

It is obvious that my improved pad and method of producing it has many advantages over the existing methods and pads, such as that my invention eliminates the time consumed and labor required in perforating those sheets which are to be later removed from the pad, the time and effort involved in fanning the perforated sheets, the time and effort involved in jogging the sheets which have been grouped into sets for a pad, and all likelihood of jogging any sheet that has been filled in as it is removed from the pad. In addition to other savings, I believe that at least 25% of the time of manufacturing a pad by the present conventional procedure will be saved by my new method.

There may be any desired number of the removable sheets 10 or 11 for each set, and any number of the carbons 13 or 14. Also, the pad may be self-binding, that is to say, it may not have a front or back cover, or it may have one and not the other. The sheets may be rectangular or square or any other desirable shape, it being only necessary that the removable sheets shall not have to be torn out but only detached where they are fastened with the pad cement or other adhesive. Also, the sheets of the sets in the pad may be printed or dittoed or the like, or may be blank sheets in whole or in part.

It will be observed that many changes or variations in detail of construction may be made without departing from the spirit and scope of my invention.

What I claim and desire to secure by Letters Patent is:

1. A record pad comprising a series of record sheets securely fastened together near an edge of the pad, removable record sheets arranged in the pad between the securely fastened sheets to form sets of record sheets, and each removable sheet being of a less dimension in one direction than the securely fastened sheets, all of said sheets being secured together at another edge of the pad by an adhesive.

2. A record pad comprising a back cover, a series of record sheets of substantially the same size as the cover securely fastened together and to the cover near an edge of the pad, removable record sheets arranged in the pad between the securely fastened sheets to form sets of record sheets, each removable sheet being of a less dimension in one direction than the securely fastened sheets, all of said sheets being secured together at another edge of the pad by an adhesive.

3. A pad comprising front and back covers of substantially equal size, a series of record sheets securely fastened together and to the covers near an edge of the pad, removable record sheets arranged in the pad between the securely fastened sheets to form sets of record sheets, each removable sheet being of a less dimension in one direction than the securely fastened sheets, all of said sheets being secured together at another edge of the pad by an adhesive.

4. A record pad comprising a series of record sheets securely fastened together near an edge of the pad, removable record sheets arranged in the pad between the securely fastened sheets to form sets of record sheets, there being at least two removable sheets between each pair of the securely fastened sheets, each removable sheet being of a less dimension in one direction than the securely fastened sheets, all of said sheets being secured together at another edge of the pad by an adhesive.

5. A record pad comprising a series of rectangular record sheets securely fastened together near an edge of the pad, removable rectangular record sheets arranged in the pad between the securely fastened sheets to form sets of record sheets, each removable sheet being of a less dimension in one direction than the securely fastened sheets, all of said sheets being secured together at another edge of the pad by an adhesive.

6. A pad comprising front and back covers, a series of record sheets securely fastened together and to the covers near an edge of the pad, removable record sheets arranged in the pad between the securely fastened sheets and between one of the securely fastened sheets and the front cover to form sets of record sheets, each removable sheet being of a less dimension in one direction than the securely fastened sheets, all of said sheets being secured together at another edge of the pad by an adhesive.

7. A record pad comprising a series of record sheets securely fastened together near an edge of the pad, removable record sheets arranged in the pad between the securely fastened sheets to form sets of record sheets, each removable sheet being of a less dimension in one direction than the securely fastened sheets, all of said sheets being secured together at another edge of the pad by an adhesive, a sheet of carbon paper arranged between a pair of the removable sheets, and a sheet of carbon paper arranged between one of the securely fastened sheets and one of the removable sheets.

8. A pad of sets of sheets of paper for recording the same information on each sheet of any of the sets, comprising sheets securely fastened together at or near one edge of the pad and having positioned between them at least one removable smaller sheet, all of the sheets being held in place by an adhesive arranged at another edge of the pad.

WARD SHAVER.
